MERCURY-VAPOR APPARATUS.

1,078,641.

Specification of Letters Patent. Patented Nov. 18, 1913.

Application filed February 1, 1912. Serial No. 674,708.

To all whom it may concern:

Be it known that I, JOSEPH C. POLE, a subject of the Emperor of Austria-Hungary, and resident of New York, county of New York, State of New York, have invented certain new and useful Improvements in Mercury-Vapor Apparatus, of which the following is a specification.

My invention relates to improvements in mercury vapor apparatus, its object being to protect such apparatus from the danger of being fractured or disabled by the shock of the shifting mercury during transportation or in the process of handling. It is, of course, well known that such apparatus usually consists of an exhausted vessel of glass or quartz with at least one electrode of mercury. The danger of fracture in the handling and transportation of these lamps is naturally one that should be guarded against, and it is to be noted that the bad effects of the shifting of the mercury usually appear at the seals of the apparatus, or at sharp bends in the tubes of which the apparatus is formed or, generally, at the weakest points in the glass or quartz structure. The likelihood of fracture or disablement exists in a considerable degree with ordinary mercury vapor apparatus having platinum wires sealed into the glass containers, but this likelihood is greatly increased when quartz lamps operating with mercury vapor under high pressure are employed. In such cases, rods of an alloy having a certain co-efficient of expansion are generally ground into the wall of the apparatus in such a manner as to form air-tight joints, and it is found that these metal rods may, by shock of mercury, be lifted from their seats and that such displacement, however slight, may be sufficient to impair the vacuum. For these reasons it is important in low pressure mercury vapor lamps and is especially important in quartz containers to provide means for protecting the endangered apparatus against the effects of shocks of mercury. For this purpose I provide small valves of glass or other suitable material which valves have a limited movement and are adapted to close off the endangered sections of the apparatus when subjected to a sudden shock, so that the mercury is not permitted to enter the endangered part or that it can enter but very slowly and without violence.

By way of illustration, I have shown in

the accompanying drawings a design of a quartz lamp with ground joints equipped with valves as described. It will be understood, however, that the valves may also serve a useful purpose in other types of mercury vapor apparatus wherein the containers are made of common glass.

In the drawings Figure 1 is a longitudinal section of a quartz lamp; Fig. 2 is a cross section of a portion thereof looking downward; Figs. 3 and 4 are detail views of one type of valve suited to the purpose of this invention, and Figs. 5 and 6 illustrate a modification of said valve.

The luminous part of the lamp is shown at 1 as a tube of glass provided with a contraction, 2, leading to the negative electrode 24 at the negative end and an off-set, 3, near the positive end, allowing for the collection of mercury at 25 to form the electrode.

At 4 is shown a laterally extending tube serving as a cooling chamber at the negative electrode, and at 5 appears the positive cooling chamber.

Leading respectively from the negative 80 and the positive electrodes 24 and 25 to the points of contact with the respective leading-in rods 20 and 21 are contracted portions, 6 and 7, within which are the respective valves, 8 and 9, furnishing the means 85 for preventing the injurious effects of shocks in apparatus of this class. These valves may be made of any suitable material such as ordinary glass or quartz glass, their function being merely mechanical. The ground portions of the glass tube are shown at 18 and 19, the former providing means for making an air-tight joint with the negative leading-in rod, 20, and the latter providing similar means for the positive leading-in rod, 21. 90 Above the ground joints are bodies of mercury, 26 and 27, to aid in securing and maintaining air-tight joints between the rods and the quartz tube.

The valve, 8, is shown on an enlarged 100 scale in Figs. 3 and 4. The valve there shown is of conical shape with a small hole, 27, in the bottom. Since the quartz is lighter than the mercury, the valve will swim in the mercury, being pressed in this way 105 against small buttons, 12, 12 (see Fig. 3) in the wall of the tube, whereby the movement of the valve is limited in extent. The lower conical part of the valve fits in a conical seat, 11, a shock caused by the movement 110

of mercury in the direction indicated by the arrow tending to fracture the knee, 16, of the lamp will, before having done harm, press the valve against this conical seat, and thus close off the endangered part of the lamp with the exception of the hole, 27, through which the mercury will be forced very slowly, thus filling gently the knee, 16.

A modified form of valve is shown at the right in Fig. 1, and on an enlarged scale in Figs. 5 and 6. Here the little swimming body has a cylindrical shape with a small flange, 13, on the top and two small vertical channels, 28, 28, on the side. The motion of the valve is again limited by buttons, 15, 15, in the wall of the vessel. By the movement of the mercury in the direction of the arrow the valve will be thrown down and the flange, being pressed against the flat seat, 14, will shut off the endangered parts of the lamp, allowing the mercury to flow but very slowly through the channels 28, 28.

The hole, 27, in Fig. 3 and the channels, 28, 28, in Figs. 5 and 6 serve also to insure an uninterrupted contact over which the electric current can pass the valve.

I claim as my invention:

1. The combination with a closed vessel having fragile walls, of a fluid in said vessel, and means for preventing shock by reason of the shifting of the position of the fluid, such means consisting of a conical valve in said vessel, a seat for said valve limiting its movement in one direction and

a positive stop for the said valve limiting its movement in the opposite direction.

2. The combination with a closed container having fragile walls, of a body of mercury in said container, and a valve having positive limits of movement in opposite directions in the path of the mercury.

3. The combination with an exhausted tube or container having a restricted portion, mercury within said tube and a valve permanently seated within said restriction and having a limit of motion away from its seat.

4. The combination with an exhausted tube or container having a restricted portion, mercury within said tube and a valve permanently seated within said restriction and having a limit of motion away from its seat, the valve being lighter than mercury.

5. The combination with an exhausted tube or container having a restricted portion, mercury within said tube and a valve permanently seated within said restriction and having a limit of motion away from its seat, the valve being lighter than mercury and being provided with an opening at its smaller end.

Signed at New York in the county of New York and State of New York this 24th day of January A. D. 1912.

JOSEPH C. POLE.
